DESIGN FOR A GARMENT BAG OR SIMILAR ARTICLE

Thomas Russell, Chicago, Ill.

Application November 25, 1946, Serial No. 135,063

Term of patent 3½ years

(Cl. D58—2)

To all whom it may concern:

Be it known that I, Thomas Russell, a citizen of the United States and resident of Chicago, county of Cook and State of Illinois, have invented a new, original, and ornamental Design for a Garment Bag or Similar Article, of which the following is a specification, reference being had to the accompanying drawing, forming a part thereof.

Fig. 1 is a perspective view of a garment bag or similar article, showing my new design.

Fig. 2 is another perspective view thereof showing the garment bag or similar article as viewed from the rear.

I claim:

The ornamental design for a garment bag or similar article, as shown.

THOMAS RUSSELL.
